UNITED STATES PATENT OFFICE.

WILLIAM A. IVES, OF NEW HAVEN, CONNECTICUT.

IMPROVEMENT IN HOLLOW AUGERS.

Specification forming part of Letters Patent No. 222,051, dated November 25, 1879; application filed August 1, 1879.

To all whom it may concern:

Be it known that I, WILLIAM A. IVES, of New Haven, in the county of New Haven and State of Connecticut, have invented a new Improvement in Hollow Augers; and I do hereby declare that the following, when taken in connection with the accompanying drawings and the letters of reference marked thereon, to be a full, clear, and exact description of the same, which said drawings constitute part of this specification, and represent, in—

Figure 1, front view; Fig. 2, rear view, showing the disk on the head; Fig. 3, side view of the head; Fig. 4, side view of the instrument complete.

This invention relates to an improvement in hollow augers—that is, instruments designed to cut round tenons, as on the ends of spokes and for similar uses, and particularly to that class which are made adjustable to cut different diameters; and the invention consists in the construction as hereinafter described, and particularly recited in the claim.

A is the head, on which are two parallel guides, B B, arranged equidistant from the center of the instrument, and constructed as a part of the body C, which terminates in a shank, D, or other device, by which the instrument may be applied to a revolving mandrel.

Between the two guides B B is a slide, E, carrying a cutter, F, the said slide arranged to be moved toward or from the center a.

On the opposite side of the center, and between the guides B B, is a second slide, F, also arranged to be moved toward or from the center. The said slide is slightly notched on its inner edge, as at b, as a rest for the material being cut, and is opposed to the cutter, so that the position of the slide F and the slide E governs the diameter of the tenon or thing to be cut, substantially as in other hollow augers.

It is essential that the two slides E and F should always retain the same relative position to the center or axis a around which they revolve, and also that when adjusted to the

required diameter they shall be firmly held in that position. To this end I arrange on the back of the head A a disk, H, concentric with the head and attached thereto by bolts d e at opposite sides, each extending through a slot, f, the said slot concentric with the head, and so that the disk may be partially rotated around the center or axis a. In this plate are two eccentric grooves h i, as seen in Fig. 2, and from the slide E is a stud, n, which enters the eccentric slot h, and from the slide F a stud, m, enters the slot i in the disk H; hence, owing to the eccentricity of the slots h i, turning the disk H will cause the two slides E F to move toward or from each other—that is, radially to or from the center a, accordingly as the disk H is turned forward or back, and, the eccentricity of the two slots being alike, it follows that the movement of the two slides will be equal.

While the slots h i in the disk will prevent the movement of the slides except when the disk is turned, it is desirable to prevent the disk from being accidentally turned. To this end one or both of the studs d e is provided with a set-nut, L, by which the disk may be clamped to the head A.

Other means than the concentric slots f may be employed as a means for securing the disk in its place on the head, it only being essential that the disk shall be arranged so as to be rotated and retain its concentric position.

It will be understood that instead of the eccentric slots h i eccentric ribs may be arranged on the disk to engage with the respective slides with the same result. I therefore do not confine my invention to the use of slots.

I am aware that it is not new to combine, in a hollow auger, a slide carrying a cutter, and a second slide forming the opposing rest, both arranged to be moved radially to and from the center for the purpose of adjustment, and therefore do not claim such invention or anything shown or described herein, except in the combination hereinafter recited.

From the foregoing it will be understood

that I do not broadly claim an adjustable cutter and rest in a hollow auger; but

What I do claim is—

The disk H, arranged on the back of the head and concentric therewith, and constructed with concentric slots f and eccentric slots h and i, combined with the two slides E

and F, connected respectively with the slots h and i and bolts e d through the slots f, all as and for the purpose specified.

WILLIAM A. IVES.
